US00D961389S

(12) **United States Design Patent** (10) **Patent No.:** **US D961,389 S**
(45) **Date of Patent:** **** Aug. 23, 2022**

(54) **CONTAINER**

(71) Applicant: **Altium Packaging LP**, Atlanta, GA
(US)

(72) Inventor: **Joseph Anthony Smarrelli, Jr.**, New Castle, PA (US)

(73) Assignee: **Altium Packaging LP**, Atlanta, GA
(US)

(**) Term: **15 Years**

(21) Appl. No.: **29/714,734**

(22) Filed: **Nov. 25, 2019**

(51) LOC (13) Cl. **09-01**

(52) U.S. Cl.

USPC **D9/516**

(57) **CLAIM**

The ornamental design of a container, as shown and described.

DESCRIPTION

FIG. 1 is a perspective view of a container showing the claimed design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines are for illustrative purposes only and form no part of the claimed design.

1 Claim, 7 Drawing Sheets
